His Attorney.

UNITED STATES PATENT OFFICE.

CHARLES F. SCHWENNKER, OF SCHENECTADY, NEW YORK, ASSIGNOR TO GENERAL ELECTRIC COMPANY, A CORPORATION OF NEW YORK.

PACKING.

Application filed November 6, 1920. Serial No. 422,301.

To all whom it may concern:

Be it known that I, CHARLES F. SCHWENNKER, a citizen of the United States, residing at Schenectady, in the county of Schenectady, State of New York, have invented certain Improvements in Packings, of which the following is a specification.

The present invention relates to packings such as are used to prevent leakage between 10 two relatively moving members, one application being in connection with a cylinder and piston to prevent leakage between them. It relates particularly to packings of the type comprising a flexible ring, such as a 15 leather ring, which is U-shaped in cross-section and is expanded by the pressure in the cylinder, such packings being ordinarily known as cup-packings.

The object of my invention is to provide 20 an improved structure and arrangement in a packing of this type and for a consideration of what I believe to be novel and my invention, attention is directed to the accompanying description and the claims appended thereto.

In the drawing, Fig. 1 shows a cylinder and piston, in the present instance a cylinder and piston of an hydraulic press, equipped with a packing embodying my invention; Fig. 2 is a perspective view with 30 parts broken away of a portion of the packing; Fig. 3 is a transverse view of the packing before it is placed in a groove in a cylinder or piston wall, and Fig. 4 is a view similar to Fig. 3 showing the packing in position in a groove.

Referring to the drawing, 5 indicates a cylinder, in the present instance, the cylinder of an hydraulic press, and 6 a piston 40 which moves therein. At 7 is an opening through which actuating fluid is admitted to the cylinder 5 beneath piston 6 and discharged therefrom. In one of the elements, as for example, in the wall of cylinder 5 is 45 a groove 8 to receive a packing.

According to my invention I provide a packing comprising an annular ring 9 of flexible material, preferably leather, which is U-shaped in cross-section whereby an annular groove 10 is formed, and in groove 10 is an annular metallic spring member 11 which likewise is U-shaped in cross-section and which serves to spread the two sides of the U-shaped ring 9 apart. The metallic 50 spring member is made preferably from a

continuous piece of wire of suitable diameter, which is reversely bent on itself as best shown in Fig. 2 to form a continuous spring member U-shaped in cross-section. Adjacent turns of the spring member are 60 spaced apart and as a result it is perfectly flexible and pliable in all directions and can be bent to any desired shape to fit in the U-shaped leather packing. The two sides of the spring member tend to normally 65 spread apart or flare outwardly as shown in Fig. 3 and when the packing is placed in a groove 8 the outer ends of the metallic spring member are squeezed together as best shown in Fig. 4. The spring member then 70 exerts an expanding pressure on the sides of the leather packing which acts to make the leather packing closely hug the piston wall and it will be noted that this pressure is applied mostly at the outer ends of the 75 two sides of the packing ring where it is most useful and most needed.

Viewed from one aspect, the spring member may be considered as comprising a plurality of U-shaped spring elements which 80 extend transversely of the packing and are held in spaced relation to each other, this latter function being performed in the present instance, by the parts of the wire which extend longitudinally of the packing. 85

Since the spring member 11 is flexible it does not interfere with the bend of the packing when inserting it in the packing groove. A cup packing with the spring member 90 therein can be twisted or bent without difficulty, to bring it to a diameter so it can be inserted in the cylinder and this in no way deranges or injures the spring member.

A U-shaped packing of this type is usually arranged with its open side facing 95 against the direction of leakage so the pressure acts to expand or spread the two sides of the packing apart to make it hug closely against the adjacent walls and in connection with my spring wire metallic expanding 100 member, it will be noted that it in no way interferes with the expansion of the packing by the pressure. This is an important consideration as it means that the force of the spring means is added directly to the force 105 of the pressure in expanding the packing.

Furthermore, the arrangement has the great advantage that it is very efficient in operation and very durable. The spring 110 expanding member may be made from cop-

per wire for example, and will not disintegrate or shed any particles which may work down into the cylinder and out through opening 7 to cause trouble in the usual control valves.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

15 What I claim as new and desire to secure by Letters Patent of the United States, is:—

1. The combination with a cylinder and a piston one of which is provided with an annular seat, of a packing member U-shaped 20 in cross section located on said seat, a plurality of spring elements U-shaped in cross section located between the sides of the packing member, whereby the free edges of the packing member are expanded into engagement with the piston and cylinder surfaces, and means for holding said elements in spaced relation to each other.

2. A packing comprising a member U-shaped in cross-section and formed from 30 flexible material such as leather, and a universally flexible metallic spring expanding member located between the sides of said first named member, said metallic spring member being formed of a piece of wire reversely bent on itself.

3. A packing comprising an annular member U-shaped in cross section and formed from flexible material such as leather, a plurality of metallic spring elements U-shaped 40 in cross section, located between the sides of

the said annular member and serving to expand its free edges, and means for holding said elements in spaced relation to each other.

4. A packing comprising an annular member, U-shaped in cross-section, and formed from flexible material such as leather, a metallic spring member U-shaped in cross-section located between the sides of the first named member, said metallic spring member being formed of a piece of wire reversely bent on itself with adjacent bends spaced apart so such member can be bent to the form desired.

5. The combination with a cylinder and 55 piston one of which is provided with an annular packing groove, of a packing in the groove comprising a ring, U-shaped in cross-section and made of flexible material such as leather, and a metallic spreader ring formed 60 of a continuous piece of wire reversely bent on itself to form a ring U-shaped in cross-section between the sides of said first-named ring.

6. A metallic spreader ring for a packing comprising a wire reversely bent on itself to form a continuous strip U-shaped in cross-section.

7. A packing comprising an annular member U-shaped in cross section and formed 70 from flexible material such as leather, a plurality of spaced spring elements located between the sides of the annular member for expanding its free edges, each spring member being U-shaped, and means for holding 75 said elements in spaced relation to each other.

In witness whereof, I have hereunto set my hand this 5th day of November 1920.

CHARLES F. SCHWENNKER.
